UNITED STATES PATENT OFFICE.

WILLARD S. PAIN, OF MERIDEN, CONNECTICUT, ASSIGNOR TO THE AEOLIAN CO., OF NEW YORK, N. Y., A CORPORATION OF CONNECTICUT.

MACHINE FOR CUTTING AND PRINTING STENCIL-SHEETS.

SPECIFICATION forming part of Letters Patent No. 690,991, dated January 14, 1902.

Application filed May 24, 1901. Serial No. 61,693. (No model.)

To all whom it may concern:

Be it known that I, WILLARD S. PAIN, of Meriden, in the county of New Haven, State of Connecticut, have invented a new and useful Improvement in Machines for Cutting and Printing Dots upon Stencil-Sheets for Use in Preparing Music-Sheets for Mechanical Musical Instruments, of which the following is a specification.

- 10 In mechanical musical instruments of the kind which are controlled by perforated music-sheets it is common in manufacturing the music-sheets to first prepare a perforated stencil-sheet, and it is customary to print a number of dots over such stencil-sheets and also to cut near the edges of such stencil-sheets a number of apertures regularly disposed and suitable for engaging with a toothed feed-wheel.
- 20 The object of the present improvement is to provide an effective machine for cutting these apertures and also printing the dots.
- 25 A machine embodying the improvement will be fully described and then its novel features will be pointed out in the claims.

In the accompanying drawings, Figure 1 is an elevation of one side of a machine embodying the improvement, certain parts being omitted to economize space. Fig. 2 is an elevation of the other side of the machine, certain parts being omitted to economize space. Fig. 3 is a plan of the machine with the middle longitudinal portion removed to economize space. Fig. 4 is a transverse vertical section at the plane of the dotted line 4, Fig. 3. Fig. 5 is an elevation of certain parts omitted from Figs. 1 and 2 and delineated as they would appear if included in Fig. 2. Fig. 6 is a view of the parts shown in Fig. 5, but as 40 they appear in a plane transverse to the length of the machine. Fig. 7 is a detail side elevation of certain parts. Fig. 8 is a view of a portion of a printed stencil-sheet.

Similar letters of reference designate corresponding parts in all the figures.

It will be readily understood from a glance at Fig. 7 that the stencil-sheet A to be prepared in this machine is to have two rows of apertures a' a^2 regularly disposed in lines 50 parallel with each other and parallel to and near the longitudinal edges of the sheet. It

will also be seen that intermediate of the two rows of apertures a' a^2 a number of rows of dots extending transversely to the length of the stencil-sheet and parallel with each other 55 are printed upon one surface of the sheet. It has been found convenient to provide in each of the rows of apertures a' a^2 twelve apertures to each foot of the length of the sheet and sixty of the transverse rows of dots a^3 to each 60 foot in the length of the sheet.

The frame B of the machine may be of any desirable construction and made of any suitable material. It is shown as comprising a table b' , having guides b^2 for coacting with 65 the side edges of the sheet to be formed into a stencil.

Above the table b' is a punch-bar C, adapted to reciprocate vertically by sliding along posts or studs b^3 , extending upwardly from 70 the table b' . The ends of the punch-bar are connected by a screw c with rods c' of eccentrics c^2 , mounted upon a shaft D, constituting the main or driving shaft of the machine. Motion may be transmitted to the shaft D by 75 means of a belt passing around a pulley d, affixed to said shaft.

The punch-bar C is provided with two punches c^3 , fitting in slideways and adjusted by set-screws c^4 . A sheet to be formed into 80 a stencil is fed under these punches, and when they descend through it they will form the first of the rows of apertures a' a^2 . When the punch-bar raises the punches, the sheet will be fed an inch forward and then allowed 85 to stop while the punches descend again to form the next apertures. This operation is repeated at the same intervals until the sheet reaches the toothed feed-wheels E, affixed to a shaft E', carrying a bed-roll E² for supporting the sheet. On this shaft is also affixed a gear-wheel E³. Opposite the bed-roll E² is a printing-roll F, having its surface properly formed for printing the rows of dots a^3 in the stencil-sheet. On its shaft F' is affixed 90 a gear-wheel F², which meshes with the gear-wheel E³. The bed-roll and the printing-roll are of the same size and rotate in opposite directions, but at uniform speed, because their gear-wheels E³ F² are also of the same 95 size. The toothed feed-wheels E are a foot in circumference at the pitch-line and each

one has twelve teeth. The bed-roll and the printing-roll are also each a foot in circumference. By adopting these proportions the stencil-sheet will be provided with twelve 5 apertures in each row a' a^2 and sixty rows of dots a^3 for every foot of the length of the stencil-sheet. Motion is imparted to the bed-roll E² by a pawl e, pivotally connected to a pawl-lever e', loosely mounted upon one of 10 the journals of said roll and coacting with a ratchet-wheel e³, which is affixed to said journal. The pawl-lever is oscillated by means of an eccentric e⁴, affixed to the shaft G and having its rod e⁴ pivotally connected with the 15 pawl-lever.

H designates an inking-roller arranged above the printing-roller F and journaled in boxes h, which are arranged in housings formed in the upper arms of levers H', which 20 are fulcrumed loosely upon the journals of the printing-roller F. The lower arms of the levers H' are connected by links h² with arms h³, affixed to a rock-shaft h⁴. Springs h⁵, fastened to the journal-box h and to the upper 25 arms of the levers H', pull down the inking-roller H, so as to make it properly coact with the printing-roller F. One of the arms h³ is connected with the rod h⁶ of an eccentric h⁷, affixed to the shaft G, and this arm h³ is 30 longitudinally slotted, so that the throw of the eccentric may be adjusted in its effect upon the lever H'. Thus the length of swing given to the inking-roller H may be varied. The journals of the inking-roller H are provided with rollers h⁸, which, just before the 35 levers H' swing into a vertical position, ride upon small rollers h⁹ (shown in Fig. 7) and lift the inking-roll H against the resistance of the springs h⁵ out of contact with the printing-roll F, so that no action of either the printing-roll or the inking-roll will have any effect upon the other. While thus elevated the inking-roll H is inked by means of a distributing-roller I, which is rotated by means 40 of a sprocket-wheel i, receiving a sprocket-chain i', which also passes around a sprocket-wheel i², affixed to the shaft G. Not only has the distributing-roll I a rotary motion, but it has a slight longitudinal motion. This it derives from the coaction with a stationary upright pin i³ of a grooved cam i⁴, which is affixed to one of the journals of said ink-distributing roll. The ink-distributing roll I is supplied with the ink by a doctor-roll J, rotating in contact with it and having the ink 45 applied to it by a knife or other suitable device.

Paper to be formed into a stencil-sheet is fed along, as already described, by means of 50 the sprocket-wheels E, which operate intermittently through the ratchet mechanism e e', actuated by the eccentric e⁴. While in motion the bed-roll and printing-roll are also in motion, and the punch-bar C with its 55 punches c³ are raised. After the paper passes these rolls it is wound up on a take-up roll, one of whose journals k is shown in Figs. 5

and 6. As the paper accumulates it will have a tendency to tear unless some provision is made to obviate any excessive speed in the 70 take-up roll as compared with the speed of the printing and bed rolls. To prevent any such excessive motion, the journal k of the take-up roll has a friction-disk k' affixed to it, and with this friction-disk contacts another friction-disk k², which is secured to rotate positively with a sprocket-wheel k³, deriving motion from a chain k⁴, which passes around a sprocket-wheel k⁵, which is affixed to the shaft G. As the disk k² may slide or 80 slip relatively to the disk k', the take-up roll will be prevented from deriving excessive speed at any time from the friction-disk k².

What I claim as new, and desire to secure by Letters Patent, is—

1. In a machine for preparing a stencil for mechanical music-sheets, the combination of a table having guides which coact with the edges of a stencil-sheet, punches for forming marginal apertures in the stencil - sheet, toothed wheels coacting with the marginal apertures of the stencil-sheet, a step-by-step feed for said toothed wheels, a printing-roll for supplying rows of parallel dots to the stencil-sheet, and means for rotating the said 95 printing-roll and supplying ink thereto.

2. In a machine for preparing a stencil for mechanical music-sheets, the combination of a table along which the stencil-sheet travels, punches for forming marginal apertures, an eccentric on a main driving-shaft for operating said punches, toothed wheels coacting with the marginal apertures of the stencil-sheet, a pawl-and-ratchet feed for said toothed wheels operated by an eccentric on the main 100 driving-shaft, a printing-roll for supplying rows of parallel dots to the stencil-sheet and means for operating said printing-roll and supplying ink thereto.

3. In a machine for preparing a stencil for mechanical music-sheets, the combination of a table along which the stencil-sheet travels, punches for forming marginal apertures in the sheet, intermittently - operated toothed wheels coacting with the marginal apertures 115 of said sheet, a printing-roll for supplying parallel rows of dots to the stencil-sheet, a take-up roll for the stencil-sheet, and a friction device to prevent excessive motion of the take-up roll.

4. In a machine for preparing a stencil for mechanical music-sheets, the combination of a table along which the stencil-sheet travels, intermittently-operated punches for making marginal openings in the stencil-sheet, a bed-roll over which said sheet passes, toothed wheels for coacting with said stencil-sheet to draw the stencil - sheet over the bed - roll, means for intermittently moving the bed-roll and the toothed wheels, and a rotary printing-roll coacting with said bed-roll for supplying parallel rows of dots to the stencil-sheet.

5. In a machine for preparing a stencil for mechanical music-sheets, the combination of

a table along which the sheet is fed, punches for making marginal apertures in the stencil-sheet, means for intermittently moving the stencil-sheet from under the punches, a printing-roll for supplying parallel rows of dots to the stencil-sheet, an inking-roller, and means for moving the inking-roller into and out of engagement with said printing-roll.

6. In a machine for preparing a stencil for mechanical music-sheets, the combination of a table along which the stencil-sheet is fed, punches for making marginal apertures in the stencil-sheet, means for intermittently moving the stencil-sheet from under the punches, a printing-row for supplying parallel rows of

dots to the stencil-sheet, an inking-roller, and means for moving the inking-roller into and out of engagement with said printing-roll, said means consisting of rocking arms in which the roller is journaled, rollers h^8 carried by the journals of the inking-roller and other rollers h^9 on which said rollers h^8 ride. 20

In testimony whereof I have signed my name to this specification in the presence of two subscribing witnesses.
